UNITED STATES PATENT OFFICE.

EDWARD A. SCHREIBER, OF CHICAGO, ILLINOIS, ASSIGNOR TO VAPOR CAR HEATING COMPANY, INC., OF CHICAGO, ILLINOIS, A CORPORATION OF NEW YORK.

WATER-HEATING DEVICE.

1,343,937.

Specification of Letters Patent. Patented June 22, 1920.

Application filed May 26, 1919. Serial No. 299,956.

To all whom it may concern:

Be it known that I, EDWARD A. SCHREIBER, a citizen of the United States, residing at Chicago, in the county of Cook and State 5 of Illinois, have invented certain new and useful Improvements in Water-Heating Devices, of which the following is a specification.

My invention relates to a water heating device of the type used in railway service for heating water either by means of a local fire or by steam taken from the locomotive boiler, the device comprising a stove or heater casing containing one or more duplex 15 pipe coils, usually two of such coils, each duplex coil consisting of two pipes one within the other, the inner one for steam and the outer one for the circulation of the water to be heated.

Considerable difficulty has been experienced in bending the ends of the outer pipe of the coil so that they will pass through the stove wall or casing of the heater in proper spaced relation with each other and 25 on horizontal lines close to and parallel to a diametrical line through the casing. In order that the terminal portions of the coil, at top and bottom, should have such position it is necessary that they should be 30 curved or bent upwardly or downwardly, as the case may be, that is, oppositely to the pitch of the turns of the coil with which they are respectively associated, and at the same time should bend, horizontally, in the 35 direction reverse to the curvature of said turns. If the extremities of the pipe itself are bent to these curvatures as has been customary, the cross sectional configuration of the pipe is likely to be changed, that is,

40 the pipe is apt to be flattened or crushed in slightly and the resultant irregularity in the cross sectional configuration of its bore at these places interferes with the uniform flow of water through the terminal portions of the coil. Moreover, it is difficult to 45 bend a pipe of this diameter accurately and accuracy is essential since the pipes must pass through and fit snugly in the holes formed for the pipes in the heater casing.

50 These holes are cut or otherwise formed before the heater is assembled so that any slight inaccuracy in the bending of the coil terminals makes the assembling of the parts of the heater difficult. Little or no diffi-

55 culty is experienced with the inner pipe of

the coil because of its relatively small diameter.

The object of this invention is to facilitate the manufacture of a duplex coil and the assembling of the coil in the heater casing by providing separately formed terminal fittings for the outer or water coil or coils which may be cast or otherwise fabricated to have a bore of substantially uniform cross sectional configuration and the proper curvatures to give such fittings the correct position in the heater casing when attached to the end turns of the coil.

The invention is illustrated in the accompanying drawings wherein

Figure 1 shows a heater having two duplex coils constructed in accordance with my invention.

Fig. 2 is a longitudinal, vertical section through one of the terminal fittings of one 75 of the coils.

Fig. 3 is a sectional plan on line 3-3 of Fig. 2.

Fig. 4 is a cross section on line 4-4 of Fig. 2.

Fig. 5 is a sectional plan on line 5-5 of Fig. 1, and

Fig. 6 is a fragmentary view, in elevation, of the upper part of the back of the heater showing the relation of the terminal 85 portions of the two duplex coils.

Like characters of reference designate like parts in the several figures of the drawings.

Except so far as the construction of the 90 duplex coil is concerned, the heater shown in the drawings is of familiar type. 10 is the cylindrical casing of the heater which is divided at the lower end with a grate 11. The heater here shown is of the base burning type, 12 being the coal magazine and 13 the stack. It will be understood that the improved coil herein claimed might be used in connection with a heater of quite different construction from that here shown. 100 Within the casing 10 are arranged two duplex coils A and B which may be substantially alike. The coil A consists of an outer water pipe 14 and an inner steam pipe 15. The upper turn 16 of the outer pipe 14 is 105 secured preferably by means of welding at 17 to a fitting 18 which is curved reversely to the curvature of the portion 16 of pipe 14 to which it is attached, as shown in Fig. 5, and is also curved reversely to the pitch 110

of the end portion of the pipe coil so that the outer end of the fitting will pass horizontally through the opening 19 in the casing close to and in parallelism with a diametrical line a, a , (Fig. 5) through the casing. The fitting 18 is tapped for a water pipe 20. The fitting is preferably cast, with the curvatures noted, and its bore is of substantially uniform cross sectional configuration from end to end of the fitting. The inner pipe 15 of the coil, the pipe through which steam is circulated, instead of terminating at the fitting 18, as in the case of the outer pipe, is continued through the fitting, being bent to correspond to the curvatures of the fitting, the projecting end 21 of pipe 15 being preferably threaded for attachment to a steam pipe. The upper end of coil B is provided with a fitting 22 similar to fitting 18 just described, and the lower ends of the coils A and B are provided with fittings 23, 24 which are arranged in reverse position from fittings 18 and 22.

I claim:

1. In a water heater, the combination of a casing having an opening through the wall thereof, a duplex coil in said casing comprising inner and outer helical pipe coils, and a fitting adapted to be attached to the end of the outer pipe coil and to pass through said opening in the casing, said fitting being curved reversely to the curvature of the portion of the coil to which it

is attached and having a bore of substantially uniform cross sectional area throughout its length, the outer end of said inner pipe coil being bent to correspond to the curvatures of said fitting and adapted to lie concentrically within the bore thereof, whereby there is provided within the bore of said fitting around said inner pipe coil an annular space of substantially uniform cross sectional area through which the heating medium may flow unobstructedly. 35

2. In a water heater, the combination of a casing having an opening through the wall thereof, a duplex coil in said casing comprising inner and outer helical pipe coils, and a fitting adapted to be attached to the end of the outer pipe coil and to pass through said opening in the casing, said fitting being curved reversely to the curvature of the portion of the coil to which it is attached and to the pitch of said portion of the coil and having a bore of substantially uniform cross sectional area throughout its length, the outer end of said inner pipe coil being bent to correspond to the curvatures of said fitting and adapted to lie concentrically within the bore thereof, whereby there is provided within the bore of said fitting around said inner pipe coil an annular space of substantially uniform cross sectional area through which the heating medium may flow unobstructedly. 40

EDWARD A. SCHREIBER.
